UNITED STATES PATENT OFFICE

2,425,382

APPARATUS FOR ADVANCING STRIP MATERIAL

Carl B. Lubbert, Anneslie, Md., assignor to Western Electric Company, Incorporated, New York, N. Y., a corporation of New York

Application April 26, 1945, Serial No. 590,377

8 Claims. (Cl. 164—116)

1

This invention relates to apparatus for advancing strip material and has for its object the provision of new and improved apparatus for advancing strip material.

In punching articles from strips of plastic material, such as polyethylene, the strips should not be stretched or the articles punched therefrom will not have uniform dimensions. One type of apparatus for punching articles from such strips includes a punch press, means for pushing strips of material toward the punch press and means for pulling the strips of material away from the punch press. It is desirable to operate the pushing means and the pulling means at separate times to prevent buckling or stretching of the strips.

An apparatus forming one embodiment of the invention comprises means for pushing a strip of material toward a punch press, means for pulling the strip of material away from the punch press and means for disengaging the pushing means from the strip when the pulling means becomes operative.

A complete understanding of the invention may be obtained from the following detailed description of an apparatus forming a specific embodiment thereof, when read in conjunction with the appended drawings, in which

Fig. 1 is a horizontal section of an apparatus forming one embodiment of the invention;

Fig. 2 is a front elevation thereof;

Fig. 3 is an enlarged vertical section taken along line 3—3 of Fig. 1;

Fig. 4 is an enlarged, vertical section taken along line 4—4 of Fig. 1, and

Fig. 5 is an enlarged, vertical section taken along line 5—5 of Fig. 1.

Referring now in detail to the drawings, a punch press 10 (Figs. 1 and 2) includes a reciprocable punch 11 and a stationary die 12. The reciprocable punch is reciprocated toward and away from the stationary die 12 by a ram 13, which is reciprocated by suitable reciprocating means (not shown) and the punch and the die serve to punch parts from a strip 15 made of plastic material, such as polyethylene. The strip may be pushed toward the punch press 10 by pushing rolls 16 and 17 and may be pulled away from the punch press by pulling rolls 20 and 21.

A rod 22 is reciprocated by the reciprocating means in synchronization with the reciprocation of the punch 11 and drives a ratchet mechanism 25, which rotates intermittently the pulling rolls 20 and 21 in opposite directions through gears 26 and 27. The ratchet mechanism 25

2

drives the pulling rolls only when the punch 11 is moved out of engagement with the strip 15. A connecting rod 30 connects the ratchet mechanism 25 with a ratchet mechanism 31, which 5 drives intermittently the pushing rolls 16 and 17 through gears 32 and 33. The pushing rolls and the pulling rolls are driven only when the punch 11 is out of engagement with the strip.

The pushing roll 16 is rotatably mounted in 10 bearings 36—36 (Figs. 2 and 4), which are mounted slidably in guideways 34—34 formed in standards 38—38 and are urged by compression springs 37—37 downwardly, as viewed in Figs. 2 and 4, whereby the pushing roll 16 is urged toward the strip 15 and the pushing roll 17. A bar 39 (Figs. 2 and 4) connecting levers 40—40 when engaged by a lobe 41 of a cam 42 holds the levers in positions in which they hold the bearings 36—36 in an elevated position so that the 15 pushing roll 16 is held out of operative engagement with the strip, whereby the strip is not pushed by the pushing rolls. The cam 42 is mounted upon a shaft 43 and has a depression 44 formed thereon. When the depression 44 is in 20 engagement with the bar 39, the compression springs 37—37 move bearings 36—36 downwardly, as viewed in Fig. 2, whereby the pushing roll 16 is moved into operative engagement with the strip 25 so that it is advanced toward the punch press 10 by the pushing rolls.

When a handwheel 45 (Figs. 1 and 2) secured to the shaft 43 is rotated in a clockwise direction, as viewed in Fig. 2, the shaft 43 is rotated and a torsion spring 46, whose ends are secured 30 to the cam 42 and a bearing 50, is wound up and the lobe 41 of the cam 42 is moved out of engagement with the bar 39, whereby the pushing roll 16 is pressed against the strip 15. When the shaft 43 is so rotated, a cam 55 secured thereto is rotated to the position shown in dotted lines in Fig. 5, at which time a shoulder 56 formed on the cam 55 is engaged by a catch 57 formed on a lever 60, whereby the shaft 43 is held against counterclockwise movement, and the pushing roll 16 is held in operative engagement with the strip.

The lever 60 is urged by a tension spring 61 in a counterclockwise direction, as viewed in Fig. 5, and the counterclockwise movement of the lever 60 is limited by an adjustable stop 62. The lever 60 is connected by a link 65 to an armature 66 of a solenoid 67. When a winding 68 of the solenoid 67 is energized, the armature is drawn downwardly, whereby the catch 57 is drawn out of engagement with the shoulder 56 and the torsion spring 46 (Fig. 1) rotates the shaft 43

in a counterclockwise direction, as viewed in Fig. 4, whereby the lobe 41 formed on the cam 42 is moved into engagement with the bar 39. This causes the levers 40-40 to move the pushing roll 16 out of operative engagement with the strip 15. The counterclockwise movement of the shaft 43 is limited by a stop 69 (Fig. 1), which engages a dog 70 fastened to the shaft 43 so that the lobe 41 formed on the cam 42 is held in engagement with the bar 39.

A pair of compression springs 71-71 (Figs. 2 and 3) urge bearings 72-72 downwardly, as viewed in Fig. 2, in guideways 78-78 formed in standards 79-79, whereby the pulling roll 20, which is rotatably mounted in the bearings 72-72, is urged toward the strip 15 and the pulling roll 21. Levers 73-73 connected by a bar 74 serve to lock the bearings 72-72 against the actions of the springs 71-71 when engaged by a lobe 75 formed on a cam 76, whereby the pulling roll 20 is held out of operative engagement with respect to the strip. The cam 76 is provided with a depression 77 and when the depression 77 is moved into contact with the bar 74, the compression springs 71-71 urge the pulling roll 20 into operative engagement with the strip. The cam 76 is rigidly fastened to a shaft 80 and an operating handle 81 also is secured thereto. When the handle is in its upper position, as viewed in Fig. 3, the lobe 75 of the cam 76 engages the bar 74. When the handle is moved from its upper position to its lower position, the depression 77 is moved into engagement with the bar 74 and the pulling roll 20 is moved by the compression springs 71-71 into operative relationship with respect to the strip, whereby the rolls 20 and 21 pull the strip through the press 10.

When the handle 81 is moved from its upper position to its lower position so that the pulling roll 20 moves into operative relationship with respect to the strip 15, an arm 82 mounted rigidly on the shaft 80 engages an actuating arm 85 of a microswitch 86 and closes the contacts (not shown) of the microswitch. The contacts of the microswitch are in series with the winding 68 (Fig. 5) of the solenoid 67, and when they are closed, the winding 68 is energized and the armature 66 thereof is drawn downwardly, as viewed in Fig. 5. This draws the catch 51 formed on the lever 60 away from the shoulder 56 of the cam 55, which permits the torsion spring 46 (Fig. 1) to rotate the shaft 43, whereby the pushing roll 16 is moved out of operative relationship with the strip so that the pushing rolls 16 and 17 cease pushing the strip at the same time that the pulling rolls 20 and 21 start pulling the strip.

In the operation of the apparatus described hereinabove, when both the set of pushing rolls 16 and 17 and the set of pulling rolls 20 and 21 are out of feeding relationship and the punch 11 is reciprocated intermittently with respect to the die 12, the strip 15 is slid manually between the pushing rolls 16 and 17 toward the punch press 10 until the left end thereof, as viewed in Fig. 2, approaches the punch press 10. The handwheel 45 then is rotated in a clockwise direction, as viewed in Fig. 2, and the shoulder 56 of the cam 55 (Fig. 5) is caught by the catch 51, whereby the pushing roll 16 (Fig. 4) is moved into and is held in operative relationship with respect to the strip. The pushing rolls then serve to intermittently advance the strip through the press.

When the left end of the strip 15, as viewed in Fig. 2, has been advanced to a position between the pulling rolls 20 and 21, which are out of

operative engagement therewith at this time, the handle 81 is moved in a counterclockwise direction, as viewed in Fig. 2. This causes the pulling roll 20 to be moved into feeding relationship with respect to the strip and the arm 82 (Fig. 3) simultaneously strikes the actuating arm 85, which closes the contacts of the microswitch 86. When the contacts of the microswitch 86 are closed, the winding 68 (Fig. 5) of the solenoid 67 is energized, whereby the armature 66 moves the catch 51 of the lever 60 out of engagement with the shoulder 56 formed on the cam 55. This permits the torsion spring 46 (Fig. 1) to move the pushing roll 16 out of operative relationship with the strip so that only the pulling rolls 20 and 21 advance the strip.

The press 10 continues to operate without any interruption and the strip 15 is pulled completely through the press by the pulling rolls 20 and 21. After the strip 15 has been advanced completely beyond the punch press 10, the handle 81 is actuated so that the pulling roll 20 is moved out of operative relationship with respect to the strip, which is withdrawn therefrom. Another strip, similar to the strip 15 then is inserted between the pushing rolls 16 and 17, the handwheel 45 is actuated to permit the pushing roll 16 to be moved into the feeding relationship with respect to the pushing roll 17, and the operation described hereinabove is repeated.

The pushing roll 16 is moved automatically out of operative relationship with respect to the strip 15 at the instant the pulling roll 20 is moved into operative relationship with respect to the strip so that no interruption in the advancement of the strip occurs. However, there is no overlapping of the periods of feeding of the pushing rolls and the pulling rolls so that no buckling or stretching of the strip is caused by possible changes in the feeding rates of the two sets of rolls. Thus, the uniformity of the articles punched from the strip is not affected adversely, as is possible where the periods of feeding of the two sets of rolls overlap.

What is claimed is:

1. Apparatus for feeding material to a punch press, which comprises means for pushing a strip of material toward the punch press, means for pulling the strip of material away from the punch press, and means for disengaging the pushing means from the strip when the pulling means becomes operative.

2. Apparatus for feeding material to a punch press, which comprises means for pushing a strip of material toward the punch press, means for pulling the strip away from the punch press, means for actuating the pushing means to stop the pushing operation thereof, and means for starting the pulling operation of the pulling means and for operating the actuating means simultaneously therewith.

3. Apparatus for feeding material to a punch press, which comprises a set of pushing rolls for pushing a strip of material toward the punch press, a set of pulling rolls for pulling from the strip away from the punch press, and means for disengaging the set of pushing rolls from the strip when the set of pulling rolls become operative.

4. Apparatus for feeding material to a punch press, which comprises a set of pushing rolls for pushing a strip of material toward the punch press, a set of pulling rolls for pulling from the punch press a strip of material pushed by the set of pushing rolls, means for moving the set of

pushing rolls into operative relationship with respect to a strip of material, means for moving the set of pushing rolls out of operative relationship with respect to a strip of material pushed thereby, means for moving the pulling rolls into operative relationship with respect to the strip, and means actuated by the last-mentioned means for actuating the means for moving the pushing rolls out of operative relationship with respect to the strip.

5. Apparatus for feeding material to a punch press, which comprises a set of pushing rolls for pushing a strip of material toward the punch press, a set of pulling rolls for pulling from the punch press a strip of material pushed by the set of pushing rolls, means for latching the set of pushing rolls in operative relationship with respect to the strip, means for moving the set of pulling rolls into operative relationship with respect to the strip, and means actuatable by the last-mentioned means for releasing the latching means.

6. Apparatus for feeding material to a punch press, which comprises a set of pushing rolls for advancing a strip of material to the punch press, a set of pulling rolls for advancing from the punch press a strip of material advanced by the set of pushing rolls, means for moving the set of pushing rolls into operative relationship with respect to the strip, means for urging the set of pushing rolls out of operative relationship with respect to the strip, means for latching the set of pushing rolls in operative relationship with respect to the strip, means for moving the set of pulling rolls out of operative relationship with respect to the strip, means for moving the set of pulling rolls into operative relationship with respect to the strip, and means operable by the last-mentioned means for releasing the latching means so that the set of pushing rolls is moved out of operative relationship with respect to the strip as the set of pulling rolls is moved into operative relationship therewith.

7. Apparatus for feeding material to a punch press, which comprises a set of pushing rolls for advancing a strip of material toward the punch press, a set of pulling rolls for advancing from the punch press a strip of material advanced by the set of pushing rolls, means for urging the set of pushing rolls out of operative relationship with respect to the strip, means for

latching the set of pushing rolls in operative relationship with respect to the strip, means for holding the set of pulling rolls out of operative relationship with respect to the strip, means for urging the set of pulling rolls into operative relationship with respect to the strip, means for releasing the last-mentioned holding means, and means operable by the releasing means for releasing the latching means, whereby the pushing rolls are moved out of operative relationship with respect to the strip.

8. Apparatus for feeding material to a punch press, which comprises a set of pushing rolls movable into and out of operative relationship with a strip of material for advancing it toward the punch press when moved into operative relationship therewith, a set of pulling rolls movable into and out of operative relationship with the strip for advancing it from the punch press when moved into operative relationship therewith, means for urging the set of pushing rolls out of operative relationship with respect to the strip, means for moving the pushing rolls into operative relationship with respect to the strip, 15 means for latching the set of pushing rolls in operative relationship with respect to the strip, means for moving the set of pulling rolls into operative relationship with respect to the strip, a solenoid having a winding for releasing the latching means when energized, a switch having normally open contacts in series with the winding of the solenoid, and means associated with the last-mentioned moving means for closing the contacts of the switch when the set of pulling 20 rolls is moved into operative relationship with the strip, whereby the set of pushing rolls is moved out of operative relationship with the strip at the same time that the set of pulling rolls is moved into operative relationship therewith.
